UNITED STATES PATENT OFFICE

VERNON D. SALTER, OF OAKLAND, CALIFORNIA

GAME APPARATUS

Application filed April 2, 1928. Serial No. 266,550.

My invention relates to toys susceptible to coin-controlled actuation.

It is the object of my invention to provide an amusing toy.

5 It is a further object of my invention to provide an automatically actuated game which may be manually controlled.

10 It is a further object of my invention to provide a coin-controlled game which may be played by more than one person.

It is an object of my invention to provide a toy simulation of pool and like games.

15 Certain of the objects of my invention relate to the improvement in construction and organization of the toy of my invention.

Other and ancillary objects of my invention will be suggested in the following description and in the use of the device of my invention.

20 Referring to the drawings:

Figure 1 is a plan view of the device of my invention. Fig. 2 is front elevation of the same. Fig. 3 is an end elevation of the same. Fig. 4 is a vertical longitudinal section of the same; the plane of section being indicated by a line 4—4 in Fig. 1. Fig. 5 is a vertical transverse section of the same; the plane of section being indicated by a line 5—5 in Fig. 1.

30 Figs. 6 to 12 are details of the operating mechanism of the device of my invention. Fig. 6 is a front elevation of the coin-controlled spring motor for driving the device of my invention. Fig. 7 is a plan view of the same. Figs. 8 and 9 are front elevational details of the coin receiver respectively in initial and final positions. Figs. 10, 11, and 12 are diagrammatic representations of the cue-actuating cam in successive positions of 35 operation.

In the device of my invention, I provide a miniature pool table 1, having holes or pockets formed therein at 1a, 1b, 1c, 1d, 1e, 1f and 1g (Fig. 1), through which balls or projectiles 2a, 2b etc. may drop; the balls being adapted to roll on the table.

45 A pan or receptacle 3, (Figs. 4 and 1), beneath the table, is adapted to catch the balls, which drop through the holes, therein. This receptacle (see Fig. 4) is tiltably supported

5 by an axle 4 extending transversely below the middle of the table 1, and secured in convenient manner to the side rails beneath the top surface of the table. The pan 3 is broad enough to underlie the holes in the table top, and extends tapering lengthwise in both directions from its axis to two opposite points near the ends of the table 1. The bottom of the pan is depressed from each side toward the center to form a longitudinal channel into 60 which the balls roll and along which they roll to one or the other end of the pan depending upon which way the pan is tilted. The pan is inclined slightly downward at its extreme ends to retain a ball thereon while either 65 end of the pan is being elevated.

Immediately above each extreme end of the pan, the table 1 has holes formed therein at 1h and 1j, through which a ball may be elevated to the upper surface of the table. Thus 70 it will be seen that balls dropping through holes 1a, 1b etc. in the table top may be raised again to the surface of the table at either 1h or 1j by tilting the pan 3 in one direction or the other. Preferably the table top is inclined very slightly toward the holes formed therein, so that stray balls will eventually be collected by the pan 3. (Of course the same result might be accomplished by inclining the table toward one edge or corner, forming 75 an opening at this lowermost position, and extending the pan 3 to underlie said opening.)

80 Means are provided for striking the balls 2a, 2b, etc. which are elevated through holes 1h and 1j. A striker in the form of a miniature billiard cue 5 or 5' is provided at each end of the table and is supported by the effigy 6 or 6' of a player.

85 Each effigy is represented as leaning one hand and forearm on the edge of the table adjacent the hole 1h or 1j; this forearm being pivoted on a vertical axis to the table; and the cue is slidable through an opening 90 formed by this hand. The other arm of each effigy is pivoted on a horizontal axis to its body, and the cue is fixed to the hand of this arm. Thus the cue may be actuated by 95 swinging one arm of the effigy, and may be 100

aimed by swinging the entire body of the effigy about its vertical axis.

The game device is completely encased; the table and effigies being supported on a floor 7, and being walled and roofed in by a rectangular glass case 8. The floor is supported (Fig. 4) by a plurality of leveling screws 9 in bosses 10 extending from the walls of a base support 11 of metal or other suitable material.

Accessible means are provided for swiveling the effigies to aim the cues. Transverse slots are formed in the floor 7 beneath the rearwardly extending foot of each effigy, and the vertical ends of bell-crank levers 12 and 12' (Figs. 1, 4 and 5) extend up through these slots and are secured to the rearwardly extending foot of each effigy. The levers are fulcrumed on horizontal pins 13 and 13' extending from the end walls of the base support 11. The long arms of these bell crank levers extend out through vertical slots in the front wall of the base support, and terminate in handles 12a and 12a'. When the handles are moved up or down, the effigies are swung in one direction or the other to aim the cues.

The forwardly extending foot of each effigy is pivoted to the floor in line with the pivot of the forwardly extending arm thereof simply to provide a supplemental support therefor. Of course either the pivot in the foot or in the arm may be dispensed with. In the latter condition, if desired, the forwardly extending foot may be positioned directly under the hole 1h or 1j so that the pivotal axis about which the effigy is moved will intersect the center of the ball to be hit.

In the illustrated positioning of the pivot point, a certain spinning action is imparted to the ball, which provides for skill of the player in addition to mere accuracy of sighting.

Automatic means are provided for actuating the cues. A connecting rod 14 or 14' (Fig. 4) is connected to the pivoted arm of each effigy, extends below the surface of the table through a guide bracket, and terminates in an ell abutment against a cam 15. A tension spring 16 joins the ends of the rods 14 and 14' (Fig. 1) and urges them upon opposite sides of the cam 15. (See Figs. 10 to 12.) The cam rises gradually to a sharp dropping-off point at 15a; at which point the follower is permitted a sharp rapid movement under influence of the spring 16. It is this movement which pulls the cue arm of the effigy forward suddenly and causes the cue to strike the ball. The cam is fixed to and rotated relatively slowly by a drive shaft 17 journaled transversely of and beneath the table surface. The drive shaft is spaced from and parallel to the axle 4 and is similarly journaled in the side rails of the table.

Means are provided for oscillating the cues

back and forth to make a feint, just as would be done by a player preparing to hit a billiard ball. The cam 15 has several undulations 15b, 15c, etc. ahead of the dropping-off point 15a. These undulations cause the cues to be oscillated several times just short of striking position before the ball is finally struck.

Coin-controlled means are provided for rotating the drive shaft 17. While it is one object of my invention to provide a toy which is readily susceptible to coin-controlled actuation; the coin-controlled mechanism itself is not new and will be described but briefly as follows:

A standard 18 projects above the front of the base support 11, and has a short horizontal operating shaft 19 (Figs. 7 to 9) journaled in its upper portion. A crank handle 20 is secured to the front of the shaft 19, and provides means for manually rotating the operating shaft.

A disc 21 is keyed to the shaft 19, and a housing 22 envelopes the disc. A coin slot is formed in the top of the housing 22, and a coin-carrying notch is formed in the periphery of the disc to receive a coin 23. The disc is normally held in coin-receiving position by a spiral tension spring 24 fixed to and extending around a drum 25 (Fig. 7) on the shaft 19 and having its free end attached to a pin 26 projecting from the housing 22.

The shaft 19 is prevented from full operative rotation, unless a coin has been deposited, by a spring-pressed pawl 27 cooperating with a notch formed at 21a in the disc 21. (The notches at 21b in the disc 21 are too small to be caught by the pawl 27 and are not affected by it.) A hump 27a on the pawl 27 is adapted to coact with a coin 23 to lift the pawl and permit full operative rotation of the shaft 19 when a coin has been properly inserted. A small spring-pressed pawl 28 coacts with the notches at 21b to prevent reverse rotation of the shaft 19 until forward rotation has proceeded far enough to drop the coin as shown in Fig. 9 into the coin-collecting base-support 11. The notch at 21a permits the pawl 28 to flip back out of restraining position after the desired amount of rotation has taken place.

An eccentric cam 29 is secured to the rear of operating shaft 19. A lever 30 (Figs. 6 and 7) is pivoted with its upper arm in the path of cam 29, and has a strong spring 31 attached to and adapted to be extended or cocked by the lower end of the lever. (The spring is shown in Fig. 6 but has been omitted from Fig. 7 to avoid confusion.) When the shaft 19 is rotated to the position shown in Fig. 9, the spring 31 is extended sufficiently to operate the entire toy through its cycle. A rack 32 (Fig. 6) is pivoted at one end to the lower end of the lever 30 and has its free

portion held by a roller 33 against a pinion 34. The pinion 34 is fixed to a shaft 35 bearing a crank 36. A free gear 37 is journaled on the shaft 35, and a spring pressed pawl 38 on the crank 36 bears against this gear 37.

5 When the spring 31 is being extended the pawl 38 permits the crank 36 to be drawn freely over the gear 37, and when the spring 31 recoils it causes rotation of the gear 37. 10 A train of step-up gears (Fig. 6) 39, 40 and 41, magnify the motion of gear 37 and transmit this motion to the drive shaft 17 afore-described to which the gear 41 is fixed.

An escapement is provided to limit the 15 speed of the train of gears. A gear (Fig. 6) 42 on the drive shaft 17 meshes with an idler gear 43 which drives a star wheel 44. An escapement stop 46 is pivoted adjacent the 20 star wheel and is provided with barbs 46a and 46b adapted alternately to catch in the teeth of the star wheel. Adjustable weights 46c and 46d are provided on the escapement stop to control the periodicity of its pendulum action, and thus to control the speed of 25 the gear train and drive shaft 17.

A complete-cycle stop (Fig. 6) is provided for halting actuation of the drive shaft. An idler gear 47 meshes with a pinion 48 on the drive shaft 17, and has a stop pin 49 thereon. 30 A lever 50 carries an abutment 50a adapted to coact with the pin 49 to stop the gear 48 after one complete revolution; thereby stopping the drive shaft after about five revolutions depending upon the ratio between gears 35 47 and 48. The outer end of lever 50 lies in the path of crank 36, and is raised by it to permit actuation of the device after the spring 31 has been extended.

The aforescribed gearing and other mechanism is considered coin-controlled 40 mechanism for rotating the drive shaft 17; which in turn automatically actuates the game of my invention as aforescribed.

Fixed on the drive shaft 17 is a second cam 45 51 to tilt the receptacle about the axis 4 to pass a ball 2b through the hole 1₁ in the table 1 just previous to the ball being struck by the striker 5'. To cause the opposite end of the receptacle 3 to elevate, a counterweight 52 is attached to the receptacle as at 53.

I have described one embodiment of my invention in detail, but it is emphasized that 50 this embodiment is illustrative and not inclusive of all the forms my invention may assume. Certain of the objects, or certain portions or combinations of the objects of my invention may be attained with the use of less than all its advantageous features or with modifications within its purview. It is petitioned that my invention be limited only by the claims constituting its final determination.

I claim:

1. In a game apparatus, a table having at 65 least three holes therein through which balls

may be passed, a tiltable receptacle underlying all of said holes and pivoted about an axis intermediate of the two extreme holes, whereby a ball dropping through a hole may be elevated through either of said extreme 70 holes to the surface of said table.

2. In a game apparatus, a table having a fixed table top provided with at least three holes therein through which balls may be passed, a tiltable receptacle beneath said holes 75 and pivoted about an axis intermediate of the two extreme holes, whereby a ball dropping through a hole may be elevated through either of said extreme holes to the surface of said table, strikers supported in operative position 80 adjacent said extreme holes, and driving means for successively tilting said receptacle and actuating said strikers.

3. In a game apparatus, a table having at 85 least three holes therein through which balls may be passed, a tiltable receptacle underlying all of said holes and pivoted about an axis intermediate of a pair of the holes, whereby a ball dropping through a hole may be elevated through either of the holes of said 90 pair to the surface of said table, strikers supported in operative position adjacent the holes of said pair, and driving means for successively tilting said receptacle and actuating said strikers; said driving means comprising a drive shaft spaced from the tilting axis of said receptacle, a cam on said shaft for tilting said receptacle, a cam on said shaft for operating said strikers, and opposed cam followers bearing on the last-recited said cam 95 100 and connected to said strikers.

4. In a game apparatus, a table having at 105 least three holes therein through which balls may be passed, a tiltable receptacle underlying all of said holes and pivoted about an axis intermediate a pair of the holes, whereby a ball dropping through a hole may be elevated through either of the holes of said 110 pair to the surface of said table, strikers supported in operative position adjacent the holes of said pair, and driving mechanism for successively tilting said receptacle and actuating said strikers.

In testimony whereof, I affix my signature.
